Inventor
Stephen D. Hartog

UNITED STATES PATENT OFFICE

STEPHEN D. HARTOG, OF ST. LOUIS, MISSOURI, ASSIGNOR TO HARRY J. HATER, OF CINCINNATI, OHIO

PISTON.

Application filed October 21, 1927. Serial No. 227,705.

My invention relates to improvements in pistons, and more particularly to pistons adapted for use in internal combustion engines and having a metallic composition which has a relatively high percentage of aluminum, magnesium or similar metals.

Better results are obtained from internal combustion engines having light weight reciprocating parts, such as the pistons, and the light weight metals used for this purpose are aluminum, aluminum alloy, magnesium and similar metals. These metals have properties which must be considered in the formation of pistons, namely, a relatively low specific gravity, a relatively high thermal conductivity, and a comparatively high thermal expansion ratio. It is the object of this invention to produce a piston using these metals, in which the latter property is rendered comparatively ineffective for all practical purposes.

An important object of this invention, therefore, is the production of a piston so constructed that the heat of combustion which causes undesirable expansion of the piston skirt, is so diverted and impeded in the course of its transmission from the head of the piston to its skirt, that its influence upon the skirt of the piston is reduced to a minimum.

Other objects and advantages of my invention will be apparent during the course of the following description.

In the accompanying drawings which form a part of this specification and wherein like characters of reference denote like or corresponding parts throughout the same,

Figure 1 is a plan view of my improved piston,

Figure 2 is a side elevation thereof,

Figure 3 is a vertical section on the line A—A of Figure 2, and

Figure 4 is a horizontal section on the line B—B of Figure 2.

In the drawings wherein for the purpose of illustration is shown a preferred embodiment of my invention the numeral 5 designates the head of the piston having a depending rim 6 in which a series of ring grooves 7 are formed to receive suitable packing rings,

not shown. The skirt 8 of the piston is separated from the head 5 and rim 6 by an opening 9. The piston skirt is relieved or completely cut away at diametrically opposite points and said cutaway portions extend from points spaced from the bottom of the skirt to the opening 9. A rib or strut 10 is arranged centrally of each cutaway portion and connects the head or rim 6 of the piston with the portion of the skirt forming the lower side of the cutaway portion. The struts 10 are offset inwardly to avoid contact with the cylinder wall and are formed integrally with the head and skirt of the piston.

The lower ends of the struts 10 are provided with elongated openings 11 which extend into the skirt 8 and divide the lower ends of the struts into spaced arms which are reinforced by strengthening ribs 12 which are arranged on the inner side thereof. The portions of the skirt immediately below the struts 10 are provided with diagonal or inclined slits 13 which extend from the bottom of the skirt into the openings 11.

Piston pin receiving hubs or bosses 14 are integrally formed on the struts 10 adjacent their center and project inwardly therefrom. The hubs 14 are provided with the usual bores 15, and while the hubs extend a substantial distance inwardly from the struts 10 they do not extend beyond the outer surface of the skirt. Transverse struts 16 connect the hubs 14, adjacent their inner ends, with the skirt 8 at the side edges of the cutaway portions. The struts 16 are arranged horizontally and function to resist the side thrust to which the piston is subjected when in operation.

It will be seen, then, that the hubs 14 are joined at their outer ends to the head and the lower portion of the skirt by the substantially vertically extending struts 10, and joined at their inner ends to the skirt by the transverse struts 16 which are arranged substantially horizontal. At a suitable position between the struts 10 and 16 there is an opening 17 dividing the inner end of each hub from the outer end thereof, and said opening may be cast with the piston, or may be cut after the piston is cast. The hubs 14 are consequently separated by the opening 17 into

spaced inner and outer portions, the inner portions being integrally connected with the struts 16 and the outer portions of the hubs 14 being integrally connected with the struts 10, there being no direct connection between the struts 10 and the struts 16 or between the separated portions of the hubs. The struts 10 and 16 are, therefore, independent of one another, and heat passing from the head 5 through the strut 10 will not be conducted to the struts 16 and the adjoining skirt portions.

In the operation of my improved piston, the head portion is subjected to direct heat generated by the explosion of gases in the combustion chamber, and this heat is conducted away through the integrally connected struts 10 and through the surrounding metal of the cylinder. The struts 10 are the only portions 20 of the piston having direct or integral connection with the head of the piston and the only path by which the heat may be conducted to the piston skirt. The heat is so reduced when it reaches the bottom of the skirt that 25 very little is transmitted upwardly to the side walls of the skirt, and is therefore comparatively ineffective due to the long and circuitous route which it must travel.

While I have shown and described the preferred embodiment of my invention, it will be understood that various changes in the size, shape and arrangement of parts may be resorted to without departing from the spirit of my invention or the scope of the 35 subjoined claims.

Having thus described my invention what I claim as new and desire to protect by Letters Patent is:

1. A piston comprising a head, skirt and piston pin hubs, each of said hubs comprising spaced portions, one of said spaced portions of each hub being connected to the head and the lower portion of the skirt, and the other portion of each hub being connected to the 45 sides of the skirt.

2. A piston comprising a head, skirt and piston pin hubs, said hubs being split whereby they are divided into spaced portions, one of said portions being joined by members with 50 the head and skirt, and the other portion of said hub being joined by members with the skirt of said piston.

3. A piston comprising a head, skirt and piston pin hubs, members joining the hubs 55 with the head and skirt, and members joining said hubs with the skirt, said hubs being split between the joining members whereby said joining members are independent of one another.

60 4. A piston comprising a head, skirt and piston pin hubs, struts integrally connecting the hubs with the head and skirt, and struts integrally connecting the hubs with the skirt of the piston, the struts being arranged in 65 spaced relation, each of said hubs being split

to form spaced portions, one of said portions being connected to one strut and the other portion being connected to the other strut whereby said struts are independent of each other.

5. A piston comprising a head, a skirt spaced from said head, said skirt being provided with diametrically opposed cutaway portions, longitudinal struts connecting the head with the portions of the skirt at the 70 lower ends of the cutaway portions and arranged adjacent the centers of the cutaway portions, piston pin hubs carried by said struts and projecting inwardly therefrom, a transverse strut connecting the inner end of 75 each hub with the skirt adjacent the side edges of the cutaway portions, said hubs being split between the longitudinal and transverse struts whereby the hubs are each divided into spaced portions, one portion connected to the longitudinal strut and the other portion connected to the transverse strut.

6. A piston comprising a head, a skirt spaced from said head and provided with diametrically opposed cutaway portions extending from the top of the skirt to a point spaced from the bottom thereof whereby a substantially continuous annular bearing surface is provided adjacent the bottom of the skirt, a longitudinal strut extending 90 across the center of each cutaway portion and integrally connecting the head with the portion of the skirt arranged at the bottom of the cutaway portion, said strut having a piston pin hub integrally formed therewith and extending inwardly therefrom, a transverse strut integrally connecting the inner end of each piston pin hub with the portions of the skirt adjacent the side edges of the cutaway portions, the hubs being split 95 between the longitudinal and transverse struts whereby the struts are each divided into spaced portions, the outer portion being connected to the longitudinal strut and the inner portion being connected to the 100 transverse strut.

7. A piston comprising a head, skirt and piston pin hubs, one of said hubs comprising spaced portions, one of said spaced portions being connected to the head and the lower portion of the skirt, and the other portion of the hub being connected to the 115 sides of the skirt.

8. A piston comprising a head, skirt and piston pin hubs, a member joining one of said hubs with the head and skirt, and a member joining said hub with the skirt, said hub being split between the joining members whereby said joining members are independent of one another.

9. A piston comprising a head, skirt and piston pin hubs, struts connecting the hubs with the head and skirt and struts connecting the hubs with the skirt of the piston, the struts being arranged in spaced relation, 130

each of said hubs being split to form spaced portions, one of said portions being connected to one strut, and the other portion being connected to the other strut whereby said struts are independent of each other, the first mentioned struts being provided with openings adjacent their lower ends which divide the lower ends of the struts into two legs, the skirt having slits extending from the bottom thereof into the openings in the struts.

10. A piston comprising a head, skirt and piston pin hubs, struts integrally connecting the hubs with the head and skirt, and struts integrally connecting the hubs with the skirt of the piston, the struts being arranged in spaced relation, each of said hubs being split to form spaced portions, one of said portions being connected to one strut and the other being connected to the other strut whereby said struts are independent of each other, the skirt beneath the first mentioned struts being provided with inclined slits extending from the bottom of the skirt into the struts.

25. 11. A piston comprising a head, skirt and piston pin hubs, a member joining one of said hubs with the head and skirt, and a member joining said hub with the skirt, said hub being split between the joining members whereby said joining members are independent of one another, the portion of the skirt beneath the first mentioned joining member being provided with a slit extending from the lower end of the skirt into said joining member.

In confirmation hereof I hereto attach my signature.

STEPHEN D. HARTOG.
